Primary Examiner — Sheryl Lane*Assistant Examiner* — Nicole Shiflet(74) *Attorney, Agent, or Firm* — Ladas & Parry LLP(57) **CLAIM**

The ornamental design for a cushion, as shown and described.

DESCRIPTION

FIG. 1 is a perspective view viewed from upper side of a cushion showing our new design;

FIG. 2 is a perspective view viewed from bottom side thereof;

FIG. 3 is a front elevation view thereof;

FIG. 4 is a right side elevation view thereof;

FIG. 5 is a top plan view thereof;

FIG. 6 is a bottom plan view thereof;

FIG. 7 is a sectional view taken along line VII-VII in FIG. 3;

FIG. 8 is a sectional view taken along line VIII-VIII in FIG. 4; and,

FIG. 9 shows the environment in which the design is associated.

The broken lines shown in the drawings represent unclaimed portions of the cushion and form no part of the claimed design.

1 Claim, 5 Drawing Sheets(56)
